WET SHEET DRIER

Stanley Wallace, Detroit, Mich.

Application May 13, 1954, Serial No. 429,668

6 Claims. (Cl. 34—94)

This invention relates to a wet sheet drier, and more particularly pertains to a laminated stack wet-sheet drier for drying wet sheets quickly and in an unwrinkled condition.

The utility and economy of wet sheet driers is well established in the photographic industry where the wet sheets of film and print are disposed between layers of blotters and corrugated boards in a laminated stack so that air is forced through the channels formed by the corrugation elements of the corrugated cardboard so as to draw off the moisture through the blotters from the wet prints and films disposed in the pack.

The devices of the prior art, however, which suitably dry prints and films and other wet sheets are large, cumbersome, and extremely expensive, especially in relation to the amateur photographer or user in that it would be necessary for him to purchase a drier which had much more capacity than was necessary and which was too expensive to buy. In other words, the matt-type driers of the prior art cost too much for the amateur or small using photographer to spend on them in relation to the use for which he would put them.

With the foregoing in view, it is the primary object of the instant invention to provide a small compact, neat, inexpensive, highly efficient, small capacity, laminated pack, wet sheet drier particularly suitable for small photographic installations.

An object of the invention is to provide a wet sheet drier which is simple and inexpensive in construction, easy to operate, efficient and uniform in operation and results, and as effective as larger much more expensive matt-type driers.

An object of the invention is to provide a sound case having a wall and sidewalls at an angle thereto defining an enclosure having a large end opening adapted to receive a rolled, laminated, tube-like pack containing the wet sheets to be dried.

An object of the invention is to dispose an air impeller wheel on the bottom wall or end wall of the case with the axis of rotation of the impeller wheel extending through the opening in the wall which receives the rolled pack.

An object of the invention is to provide a deflector wall surrounding the wheel inside the enclosure or casing.

An object of the invention is to provide a tubular, laminated, rolled pack with a relatively large central opening adapted to feed air axially of the fan when the pack is disposed in the casing.

An object of the invention is to provide channels in the wall area of the pack adapted to channel air received from the fan outwardly of the casing or enclosure.

An object of the invention is to provide a deflector wall around the impeller wheel adapted to deflect the radially impelled air axially outwardly of the casing through the opening in parallel with the axis of rotation of the impeller wheel.

An object of the invention is to provide a plenum chamber adjacent the radial area of the fan for receiving the

2

radially impelled air so as to provide even distribution of the impelled air to each and every channel or duct leading through the pack.

These and other objects of the invention will become apparent by reference to the following description of the roll type matt pack drier embodying the invention taken in connection with the accompanying drawing, in which:

Fig. 1 is a vertical cross-sectional view of a drier embodying the invention with parts being shown in elevation;

Fig. 2 is a top elevational view of the inventive drier as seen in Fig. 1, including a portion of the rolled laminated pack as seen in Fig. 1 but eliminating the rest of the pack as seen in Fig. 1.

Referring now to the drawings where like numerals refer to like and corresponding parts throughout the several views, the wet sheet drier disclosed therein to illustrate the invention, comprises a bottom wall 10 and sidewalls 11 and 12 disposed at an angle to the bottom wall 10 which in conjunction with the angled walls 11A and 12A comprise a case or describe an enclosure having a top opening 13. As seen in Fig. 1, the walls may be provided with an enlarged base portion 14 and inwardly directed lip portions 16 and 17 having a rubber sealing grommet 18 thereon for sealing against the outer edge wall of the laminated pack 20 disposed in the opening 13 of the case.

Mounted on the wall 10, which is opposite the opening 13, is the motor 21 which supports the air impeller wheel 22 with its axis of rotation as extended aligned with the central area of the opening 13 so that when the pack 20 is disposed therein the large center opening 23 in the pack 20 is axially aligned with the impeller wheel's axis of rotation. It is to be noted that the bottom 24 of the pack 20 rests on the walls 11A and 12A with the bottom 24 of the pack disposed on substantially the same plane as the top 25 of the impeller wheel 22.

The pack 22 in the thick wall area 26 is provided with channels or chambers 27 which parallel its center opening 23 and which parallel the impeller wheel's extended axis of rotation.

In assembling the pack 20, it is preferable to lay a long strip of corrugated cardboard on a flat surface so that the corrugations thereof run cross-wise of the strip, which corrugations form the channels 27 of the integrated pack. A strip of blotter is superimposed coextensively on the cardboard strip and the wet prints or sheets or films are then laid on top of the blotter. Another strip of blotter is laid over the wet sheets and the whole laminated group is then rolled into the pack as seen in the drawing as designated by the numeral 20.

In operation, with the impeller wheel 25 turning at a substantially high rate of speed, the air in the area of the blades 40 is thrown sidewise outwardly radially of the impeller wheel 25, into the plenum chamber area P of the enclosure as described by the walls 11A and 12A and the bottom of the pack 20. As the radially impelled air strikes the walls 11A and 12A, it is directed upwardly axially parallel with the axis of rotation of the fan to the bottoms or ends of the chambers 27 in the pack 20. Due to the outward radially impelling of the air in the area of the blades 40, a low pressure area is created at the end 41 of the fan and atmospheric pressure forces a constant supply of air into the central opening 23 of the pack 20 so that the fan or impeller wheel is constantly supplied with air so that it can constantly radially direct and force air into the plenum chamber P, where it feeds evenly outwardly through the chambers 27 in the direction of the arrows 42, absorbing the moisture in the pack so as to accelerate drying the wet sheets contained therein.

While the inventive device is shown in an embellished and highly finished state of construction, it is evident that the enclosure can be formed with simple cylindrical

sidewalls and a bottom connected thereto to support the motor 21 and the impeller wheel 25. It is also obvious that the pack 20 can be suspended at the upper end of the walls defining the disclosure.

Although but a single embodiment of the invention has been shown and described in detail, it is obvious that many changes may be made in the size, shape, detail, and the arrangements of the elements of the invention within the scope of the appended claims.

I claim:

1. A photograph print and film drier comprising a case having a large opening in one side thereof, a powdered air impeller wheel in said case on the side thereof opposite the opening; said wheel being axially aligned with the opening; a partition wall inside said case surrounding said wheel disposed on an angle inclining outwardly toward said opening, and a pack in said case disposed in said opening abutting the side walls thereof and extending through the interior of said case and abutting said partition wall; said pack having a hollow central portion axially aligned with said wheel axis and a longitudinally chambered area surrounding said central hollow portion; said pack bottom being substantially on a plane with the top of said wheel; said wheel when running being capable of drawing air into said case through said pack central opening and discharging the air from said case through said pack longitudinal channels so as to force air through said pack to absorb moisture from prints and film laminated in said pack.

2. A photographic print and film drier comprising a cylindrical case having a large top opening, a bottom in said case, a powdered air impeller wheel on said bottom having its axis of rotation when extended leading through the center of the case top opening, a truncated conical partition wall in said case adjacent said bottom surrounding said wheel with the larger end thereof uppermost and contacting the inside of said case, a corrugated cardboard rolled laminated pack adapted to have wet prints and films integrated therewith disposed in said case opening in sealing relationship with the side walls thereof and in sealing relationship with said conical partition wall; said pack being rolled from a long strip of corrugated cardboard so that when rolled said pack has the characteristics of a thick-walled hollow-centered tube with longitudinal channeling in the wall area and a hollow center area; said pack bottom being on substantially the same plane as said wheel top; said wheel when running being capable of drawing air into said case via said pack hollow center area and discharging air from said case through said pack lon-

gitudinal channel area so as to force air through said pack to absorb moisture from prints and films laminated in said pack.

3. A wet sheet drier comprising a first wall, a powered impeller wheel mounted on said wall, second walls connected to said wall at an angle thereto together with said first wall defining a wheel enclosure having a large opening; said wheel being aligned relative to the enclosure opening with said wheel's extended axis of rotation projecting through the central area of said opening; said wheel being adapted to draw air axially and to thrust air radially thereof so as to circulate air in said enclosure, and divider means in said enclosure separating said wheel's air drawing axial portion from said wheel's thrusting radial portion to channel the air in said enclosure and prevent short circuiting of the air between said wheel's drawing and thrusting portions.

4. In a device as set forth in claim 3, an inclined deflector wall surrounding said wheel adapted to intercept radially thrust air and direct it parallel to said wheel's axis of rotation.

5. In a device as set forth in claim 3, said divider means constituting a thick-walled laminated pack having a relatively large center opening and relatively smaller channels in the wall area thereof; said pack being disposable in the opening of said wheel enclosure in sealing relationship with said second walls with said pack's central opening and side channels in parallel with said wheel's axis of rotation with said pack's first inserted end lying substantially on the same plane as the top of said wheel; said wheel when running being capable of drawing air into said enclosure via said pack central opening and to force the air outwardly of said enclosure via said pack side channels.

6. In a device as set forth in claim 5, an inclined deflector wall surrounding said wheel adapted to contact and support said pack in desired location on the plane of the top of said wheel and to intercept radially thrust air and direct it parallel to said wheel's axis of rotation through said pack.
